FIG. 3.

Owen H. Spencer
Inventor

UNITED STATES PATENT OFFICE

OWEN H. SPENCER, OF INDIANAPOLIS, INDIANA

ENGINE MANIFOLD CONSTRUCTION AND ARRANGEMENT

Application filed June 11, 1929. Serial No. 369,997.

This invention relates to manifold constructions of that class adapted primarily for use in connection with internal combustion engines and one feature of the invention is the provision of means for attaching the manifolds in such manner that one or more of the cylinders of the engine may be removed without disarranging the connections of the manifolds with the other cylinders of the engine not being removed.

A further feature of the invention is the provision of means for attaching a plurality of manifolds in position over their respective ports with the employment of a minimum number of securing elements.

A further feature of the invention is the construction of manifolds for connection with cylinders having integral or solid heads.

A further feature of the invention is the provision of means for conveying the exhaust from both the upper and lower ends of the cylinder thru a single manifold.

A further feature of the invention is the provision of means for conveying air to parts of the engine for cooling the same.

A further feature of the invention is the provision of means for conveying air to the interior of the engine for aiding the discharge of the exhaust and for scavenging purposes.

Other objects and advantages will be hereinafter more fully set forth and pointed out in the accompanying specification.

In the accompanying drawings which are made a part of this application,

Figure 1 is a side elevation of the upper portion of an engine, showing an intake and exhaust manifold attached thereto, with parts thereof in section.

Figure 2 is a horizontal sectional view near the dotted line 2—2, Fig. 1.

Figure 3 is a vertical sectional view substantially along the line 3—3, Fig. 2.

Referring to the drawings in which similar reference numerals designate corresponding parts thruout the several views, the numeral 1 designates the cylinders of an engine, preferably of the internal combustion type, the top portion or head 2 of which is preferably integral with the cylinder proper.

The head 2 is provided with an intake port 3 and an exhaust port 4, which are controlled by the usual form of valve structures 5 and 6, respectively, and these valves are opened in the conventional manner by means of rocker arms 7 and 8, which are operated thru the conventional rods 9 and 10, tappets 11 and cams 12.

Cooperating with the ports 3 is an intake manifold 13, having substantially vertically extending elbows 14, the discharge ends of which register with the ports 3, the faces of said ports and ends of the elbows cooperating therewith, fitting flush with each other.

At the lower extremity of each cylinder 1 is an exhaust port 15, with which cooperates an exhaust manifold 16, said manifold having openings 17, the ends of which fit flush with the end faces of the exhaust ports 15. The exhaust manifold 16 also has a plurality of elbows 18, the free ends of which fit flush against the ends of the exhaust ports 4, the ends of the elbows connecting with the manifold 16 being in advance of the openings 17, so that the exhaust discharging thru the elbows 18 will not interrupt or affect the discharge of the exhaust thru the openings 17, but will aid in expelling the exhaust entering thru the openings 17 from the exhaust manifold.

On the opposite side of the cylinders 1 from the intake and exhaust manifolds, is a pair of air conveying manifolds 19 and 20, the manifold 19 conveying air from any suitable source to air chambers 21, while the manifold 20 conveys air to air jackets 22 surrounding the cylinders 1, preferably at points receiving the greatest amount of heat incident to the explosions of the gaseous fuel used for operating the engine. The air enters the cylinders 1 from the chambers 21 thru ports 23, which air acts to dilute the fuel charge as well as scavenging the cylinders and aiding in forcing the exhaust from the cylinders, a valve 24 being arranged for controlling the passage of the air thru the port 23.

The air jackets 22 preferably entirely surround the cylinders 1 and the air entering the same from the manifold 20 escapes thru bores 25 (see Fig. 2), which preferably extend

vertically thru the head portions 2 of the cylinders, the placing of the bores in this manner aiding in the discharge of the air from the jackets 22, owing to the tendency of heat to naturally ascend when released.

5 The openings 26 and 27 in the manifolds 19 and 20, respectively, fit snugly against the openings 28 and 29 in the chamber 21 and jackets 22, respectively, and the manifolds 19 and 20 are held in fixed relation with their respective parts by means of bolts 30 and clamping arms 31 on the ends thereof, said clamping arms spanning said manifolds 19 and 20, while the bolts 30 extend transversely of the engine and preferably between the cylinders 1.

10 The same bolts 30 serve to clamp the exhaust manifold 16 in position on the engine, said bolts passing thru lugs 32 on the top edge of the manifold 16, nuts 33 being threaded onto the bolts for clamping the manifolds 16, 19 and 20 in fixed positions.

15 The intake manifold 13 and the free ends of the elbows 18 are clamped in position over the ports 3 and 4, respectively, by means of stud bolts 34, the inner ends of which are preferably threaded into parts of the cylinders 1, clamping arms 35 being placed on the bolts 34 and spanning the elbows 14 and 18 20 of the intake manifold 13 and exhaust manifold 16. By connecting the elbows 14 and 18 in this manner, but a single bolt 34 is required for attaching the pairs of elbows to each cylinder.

25 30 The end faces of the ports 3 and 4 are in vertical alignment with the faces of the exhaust ports 15 and the faces of the openings 29 to the jackets 22 are in vertical alignment with the faces of the openings 28 into 35 the chambers 21, so that by loosening the bolts 30 on opposite sides of any particular cylinder, and loosening the bolt 34 with that particular cylinder, said cylinder may be removed without dismantling the manifolds or 40 without disturbing the other cylinders. In returning the cylinder to position on the engine base, it is but necessary to properly register the ports therein with the respective openings in the several manifolds and then tighten 45 the bolts previously released, in order to secure the manifolds to the cylinder.

50 The faces of all the openings in the manifolds on either side of the cylinders are in alignment with each other so that all such 55 faces may be machined at one operation, and likewise the faces of the various port openings in the engine cylinders are so arranged that all the ports on one side of the cylinder may be machined at one operation, thereby 60 greatly reducing the cost of manufacture as well as insuring a perfect fit between the port faces and the openings in the various manifolds.

65 While the description and drawings illustrate in a general way certain instrumental-

ities which may be employed in carrying the invention into effect, it is evident that many modifications may be made in the various details without departing from the scope of the appended claims, it being understood that the invention is not restricted to the particular examples herein described.

70 I claim as my invention:

1. The combination with the cylinders of an engine, each having an exhaust port at one side thereof, and air receiving openings on the opposite side thereof from the exhaust port, of an exhaust manifold for cooperation with said exhaust ports, a pair of air conveying manifolds for cooperation with said air receiving openings, and means extending transversely of the engine for clamping all of said manifolds in engagement with the cylinders of an engine.

75 80 85 90 95 2. The combination with the cylinders of an engine having exhaust ports at one side and air inlets on the opposite side, and openings for cooperation with said ports and inlets, of means extending transversely between said cylinders for clamping said manifolds in engagement with said cylinders, whereby, when certain of said clamping means are released certain of said cylinders may be removed or assembled without dismantling said manifolds.

100 105 110 115 120 125 3. The combination with the cylinders of an engine each having an exhaust port at its lower extremity and a pair of air receiving openings on the opposite side thereof one above the other, of an exhaust manifold having openings for registration with said exhaust ports, a pair of air conveying manifolds having openings for registration with the air ports of the cylinders, and bolts extending transversely of the engine adapted to clamp all of said manifolds in position over their respective ports.

In testimony whereof, I have hereunto set my hand on this the 31st day of May, 1929
A. D.

OWEN H. SPENCER.
